CLAIM

The ornamental design for a pen grip, as shown and described.

DESCRIPTION

FIG. 1 is a top perspective view of a pen grip, showing my new design.

FIG. 2 is a bottom perspective view thereof.

FIG. 3 is a left side view thereof.

FIG. 4 is a right side view thereof.

FIG. 5 is a front elevational view thereof.

FIG. 6 is a rear elevational view thereof.

FIG. 7 is a top plan view thereof; and,

FIG. 8 is a bottom plan view thereof.

The broken lines showing certain wording is for the purpose of illustrating unclaimed subject matter and form no part of the claimed design.
